CLAIM

The ornamental design for a vomit container, as shown and described.

DESCRIPTION

FIG. 1 is a front view of a vomit container showing my new design.

FIG. 2 is a rear view thereof.

FIG. 3 is a left side view thereof.

FIG. 4 is a right side view thereof.

FIG. 5 is a bottom view thereof; and,

FIG. 6 is top view thereof.

The details shown in broken lines form no part of the claimed design.
